UNITED STATES PATENT OFFICE.

THEODORE ALONZO LANSCHA, OF CHENOA, ILLINOIS.

WATER-HEATER.

1,174,998.

Specification of Letters Patent. Patented Mar. 14, 1916.

Application filed May 26, 1915. Serial No. 30,583.

To all whom it may concern:

Be it known that I, THEODORE A. LANSCHA, a citizen of the United States, residing at Chenoa, in the county of McLean and State 5 of Illinois, have invented a new and useful Water-Heater, of which the following is a specification.

The device forming the subject matter of this application is adapted to be employed 10 for heating stock tanks, and one object of the invention is to provide a means whereby a fire may be maintained exteriorly of the tank, it being unnecessary to introduce the heater directly into the tank as has sometimes been proposed hitherto.

Another object of the invention is to provide a means whereby the heater may be drained readily when not in use, thus preventing a freezing of water in the heater and 20 in the pipes which form an operative connection between the heater and the tank.

It is within the province of the disclosure to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawing: Figure 1 shows the invention in top plan, parts being broken away; Fig. 2 is a vertical longitudinal section of the heater; Fig. 3 is a transverse section taken through the heater and the tank, parts appearing in elevation; Fig. 4 is a fragmental vertical section of the controlling valve which is located in the tank; Fig. 5 is a fragmental transverse section on the line 5—5 of Fig. 4; Fig. 6 is a fragmental top plan showing a modified form of the invention. Fig. 7 is a cross sectional view showing a modified form of the invention.

50 In carrying out the invention there is provided a heater 1, and in this connection it is to be understood that the heater may be va-

riously constructed without jeopardizing the utility of the invention. In general, large latitude in the construction of the heater 1 is permissible, and the following description is to be taken as indicating one type of heater which may be used, rather than as indicating that a heater of any specific sort must be employed.

The heater includes a body 2 having an extension 3 supported on one or more legs 4, the numeral 5 indicating a stack which communicates with the extension 3. Located in the body 2 of the heater 1 is a grate 6 above which is disposed a fire box 7. The body of the heater may be equipped with a clean-out door 8 and may be provided with a removable lid 9 whereby fuel may be inserted onto the grate 6.

Disposed within the body portion 2 of the heater 1 is a looped pipe 10 at the bend of which is disposed a drain pipe 11 extended outwardly through one end of the heater 1, the drain pipe 11 being controlled by a cut off valve 12. The looped pipe 10 comprises arms 14 extended through the side wall of the heater and extended through the side wall of a tank 15, suitable packing devices 16 being provided in connection with the arms 14 in order to prevent leakage where the arms pass through the side wall of the tank 15.

The arms 14 enter one end of a casing 17 a portion of the top of which is inclined as shown at 18, the casing being located within the tank 15 and preferably resting on the bottom of the tank. A closure 19 is hinged as shown at 20 to the casing 17 and is adapted to coact with the inclined edge 18 thereof, the closure 19 carrying a resilient packing 21 of any desired sort, adapted to form a water tight joint between the closure 19 and the inclined edge 18 of the casing 17. A resilient means is provided for maintaining the member 19 in a closed position and this resilient means may be of any desired construction. In the present instance, a retractile spring 22 is located within the casing, one end of the retractile spring being secured to the bottom of the casing, and the other end of the spring being secured to the closure 19. An actuating member for the closure 19 is provided, the actuating mem-

ber, if desired, being in the form of a cord 23 adapted to be engaged with a hook 24 or the like mounted on the side wall of the tank 15 as will be understood clearly from 5 Fig. 3.

In the modified form of the invention shown in Fig. 6 of the drawings, the tank is shown at 25 and the arms of the looped pipe is shown at 26, each arm 26 carrying 10 a casing 27 provided with a hinged closure 28, and each closure 28 being actuated by a separate cord 29, both of the cords being adapted to be assembled with a securing device 30 mounted on the side wall of the tank.

15 In practical operation, when a fire is built in the heater 1, the water will circulate from the tank through the pipe 10 and be heated to a high degree, the temperature in the tank 15 being raised accordingly, and being kept 20 well above freezing point by the hot water or steam which is delivered into the tank from the heater 1 through the pipe 10. Continued circulation of the heated water will be maintained. While this circulation is going 25 on, the closure 19 is raised and is held raised by the cord 23. The cord 23, however, may be released at any time, whereupon the spring 22 will move the closure downwardly, and prevent further circulation through the 30 looped pipe 10. The valve 12 then may be opened, effecting a thorough drainage of the pipe, it being observed, as shown at 31 in Fig. 3, that the pipe 10 and its branches 14 slant downwardly from the tank toward the 35 heater, to promote a drainage through the pipe 11.

The operation of the structure shown in Fig. 7 does not differ materially from the 40 operation of the structure hereinbefore described, saving for the fact that each of the closures 28 must be manipulated separately by its actuating member 29. In Fig. 7 of the drawings, the heater is shown at 50 and the tank 51, the controlling means being indicated at 52. One branch of the loop-shaped pipe is shown at 53, and slants slightly from the tank toward the heater, as hereinbefore described. The other branch of the loop-shaped pipe is carried upwardly, 45 to form a loop 54, the uppermost portion of which lies above the upper edge of the tank 51. The part shown at 54 remains free of 50

water at all times and is adapted to be traversed by steam as the same enters the tank.

Having thus described the invention, what 55 is claimed is:—

1. In a device of the class described, a tank; a box-like casing disposed within the tank and provided with an opening; a vertically swinging lid hinged to the casing and 60 forming a closure for the opening; an operating member connected to the lid and extended upwardly to a point adjacent the top of the tank; means for holding the operating member in adjusted positions thereby to secure an opening and a closing of the lid; a heater; and a pipe extended from the heater, the pipe passing into the tank and communicating with the casing.

2. In a device of the class described, a 70 tank; a casing in the tank and provided with an opening; a vertically swinging lid hinged to the casing and forming a closure for the opening; a retractile spring located within the casing and connected to the lid 75 and the bottom of the casing; an operating member connected to the lid and extended upwardly to a point adjacent the top of the tank; means for holding the operating member in adjusted positions thereby to secure 80 an opening and a closing of the lid; a heater; and a pipe extended from the heater, the pipe passing into the tank and entering the casing.

3. In a device of the class described, a 85 tank; a casing in the tank and provided with an opening; a vertically swinging hingedly mounted lid coacting with the casing and forming a closure for the opening; spring means for maintaining the lid in a closed position with respect to the opening; a flexible element secured to the lid and upwardly extended to a point adjacent the top of the tank; tank carried means for engaging the flexible element; a heater; and a pipe ex- 90 tended between the tank and the casing.

In testimony, that I claim the foregoing as my own, I have hereto affixed my signature in the presence of two witnesses.

THEODORE ALONZO LANSCHA.
